SAFETY ENVELOPE

Joseph Kubinyi, Canton, Ohio

Application March 9, 1939, Serial No. 260,823

1 Claim. (Cl. 229—78)

This invention relates to certain new and useful improvements in safety envelopes.

The primary object of the invention is to provide a safety envelope wherein a lock device is associated with the sealing or closure flap and back wall of the body of the envelope to prevent opening of the envelope other than by tearing or cutting so that unauthorized tampering with the closed envelope may be readily detected.

10 A further object of the invention is to provide a safety envelope of the foregoing character wherein the lock device for the closure flap is of such character that opening of the envelope is impossible without tearing the same, the lock device 15 including an element positioned within the envelope and operable exteriorly of the envelope to accomplish the locking operation of the lock device.

With the above and other objects in view that 20 will become apparent as the nature of the invention is better understood, the same consists in the novel form, combination and arrangement of parts hereinafter more fully described, shown in the accompanying drawing and claimed.

25 In the drawing:

Figure 1 is a rear elevational view of an envelope equipped with the lock device of this invention.

Figure 2 is an enlarged fragmentary rear elevational view of the envelope shown in Figure 1, with the bolt element of the lock device in its released position as illustrated by dotted lines upon the initial closing of the envelope flap,

Figure 3 is a fragmentary rear elevational view, 35 similar to Figure 2, showing the lock bolts of the lock device projected to their locked positions with the flap of the envelope permanently closed,

Figure 4 is a fragmentary inner face view of the rear wall of the envelope showing the lock device thereon and in its locked position,

Figure 5 is a vertical cross sectional view taken on line 5—5 of Figure 2,

Figure 6 is a perspective view of the lock bar or strap of the lock device,

45 Figure 7 is a perspective view of the pin for retaining the lock bolts in their retracted positions, and

Figure 8 is a fragmentary plan view of the flap of the envelope showing openings therein for the 50 passage of the lock bar or strap of the lock device.

The envelope with which the lock device is associated is of the usual construction having a front wall 10, a rear wall 11 and a closure flap 12.

The lock device for the closure flap 12 comprises a relatively thin cardboard plate 13 ad-

hesively or otherwise secured to the inner face of the back wall 11, the cardboard plate 13 having therein a relatively large rectangular opening 14. A substantially U-shaped resilient wire frame has side legs 15 and a connecting cross leg 16, the cross leg 16 being secured to the lower end of the cardboard plate 13 by means of the inclosed paper or fabric strap 17, while the upper ends of the side legs 15 that by their inherent resiliency move away from each other are bent at right angles outwardly providing lock bolts 18, the upper ends of the side legs 15 as illustrated in Figure 4 being positioned laterally of the central opening 14 in the cardboard plate 13.

10 A lock bar or strap is associated with the tensioned bolts 18 and, as shown in detail in Figure 6, the lock bar or strap 20 has angularly bent ends 21, each of which has an opening 22 therein providing keepers for the two lock bolts 18.

15 The flap 12 of the envelope as shown in Figure 8 is provided with a pair of spaced openings or slots 23 and similarly formed openings are provided in the back wall 11 of the envelope and the upper end of the cardboard plate 13 for the passage of the angle ends 21 of the lock bar or strap 20 and the interior of the envelope as shown in Figure 5.

20 To retain the lock bolts 18 in their retracted positions as shown by dotted lines in Figure 2, a pin 24 shown in detail in Figure 7 is provided and 30 has latch ends 25 bent at right angles thereto, the latch ends of the pin 24 being engaged with the side legs 15 for holding them against separation and with the outer ends of the bolts 18 inwardly and laterally of the openings 23 in the 35 flap 12. A flexible cord 26 is looped around the pin 24 intermediate the ends thereof and both of the strings 26 pass through an opening 27 in the back wall 11 of the envelope to depend below the flap 12 as shown in Figures 1, 2 and 5.

40 After the contents are placed in the envelope, the closure flap 12 is folded into closed position and the lock bar or strap 20 then has the ends 21 thereof passed through the openings 23 in the flap 12 and registering openings in the back wall 45 11 and cardboard plate 13 with the keeper openings 22 in the angle ends 21 of the lock bar aligned with the lock bolts 18. A pull on the string 26 disengages the latch ends 25 of the pin 24 from the side legs 15 that carry the lock bolts with the resiliency of the side legs 15 outwardly projecting the lock bolts 18 for passage into the keeper openings 22 in the lock bar ends 21. A pull on one end of the string 26 completely removes the 50 55

string from the envelope and with the latch pin 24 displaced from the side legs 15, the lock bolts 18 remain permanently positioned in the keeper openings 22 for the securer sealing of the envelope 5 flap 12.

While there are herein shown and described the preferred embodiments of the invention, it is nevertheless to be understood that minor changes may be made therein without departing 10 from the spirit and scope of the invention as claimed.

I claim:

In an envelope and fastening device therefor, an envelope having front and back walls and a 15 hinged closure flap, a plate secured to the inner

face of the back wall, a U-shaped spring device having the bight thereof attached to said plate, the side legs of the spring device, each having an outwardly directed lock bolt at its free end, means releasably engaged with said legs for normally restraining outward separating movements of the legs before sealing the envelope, a lock bar having apertured angle ends with the ends passed inwardly through the flap and back wall with the lock bolts receivable in the apertured ends, said 10 means including a pin having latch ends releasably engageable with the side legs and a pull cord attached to the pin and extending through the back wall.
